GRINDSTONE WHEEL DRESSER

Andrew J. Engle, Chicago, Ill., assignor of one-half to James E. Kennedy, Chicago, Ill.

Application May 1, 1947, Serial No. 745,266

2 Claims. (Cl. 125—11)

1

This invention relates to an improved type of a grindstone or emery wheel surface dressing device. It is particularly adapted to provide uniformly applied pressure to the cutting face of the grinding wheel surface.

In dressing the face of a worn down grindstone, an operator holds to the edge thereof a dresser tool which consists of a series of freely revolving toothed wheels moving about a common shaft. The shaft is mounted in a yoke or a U-type holder. The latter is generally mounted in a wooden handle to provide a suitable and convenient means to hold the tool while it is in use. The Soderstrom Patent Number 1,395,606 is illustrative of one type. Another type is shown in the Patent Number 602,106 to Charles E. Roberts. Though there are many others these will serve as typical examples and will illustrate the present types used by the tool industry to refurbish grinding wheels.

In resurfacing grindstones and similar devices, the operator generally presses a hand type grindstone reconditioner such as shown by Soderstrom for example, against the outer periphery of the grindstone. The first impulse of most operators is to press quite heavily the reconditioning tool or dresser against the grindstone surface. By doing so, the grindstone is dressed more quickly. Unfortunately the pressure is not uniformly applied for no matter how hard the operator tries to do so it varies as the surface is dressed. Therefore the application of uniform pressure to the grindstone is haphazard. Thus in time the grindstone tends to be out of round and develops high and low spots. Such spots and variations in the roundness of the grindstone are decidedly disadvantageous for a craftsman using such deficient grindstone cannot properly sharpen his tools, cutting edges or even dress down to dimensional requirements a job without encountering considerable loss of time, patience and economies of operation.

In addition many grindstones of natural stock or even of the so called better quality having synthetic binders therein frequently have faults and "soft spots" and shoulders within their structure. In the course of usage such faults and soft spots are worn out more rapidly and the depletion of the grindstone is considerably greater. The gouging or unevenness in the surface of the grindstone caused by excessive wear at such faults and soft spots is further accentuated since a dresser when applied to the face or periphery of such a grindstone tends to follow the contours of the worn out hollows and therefore the depletion of the grindstone by gouging is increased

2

considerably. In the hands of an extremely skillful grindstone dressing mechanic, a good deal of the unevenness can be removed with a manually operated dressing tool. Nevertheless, the grindstone never recovers fully its overall efficiency, and cannot be usefully employed on projects or jobs requiring extremely careful and close tolerance grinding.

It therefore is an object of my invention to provide an improved grindstone dressing device that will apply pressure to the face of the grindstone at a uniform rate.

A further object of my invention is to provide an improved grindstone dressing device than can be easily, conveniently and readily attached to the framing of the grindstone while dressing the peripheral surface thereof.

A still further object of my invention is to provide an improved grindstone wheel dressing device wherein the pressure on the surfacing gear can be uniformly transmitted without gouging or pitting of the peripheral grinding surface of the grindstone.

A still further and additional object of my invention is to provide a mechanical grindstone surface dressing device wherein additional pressure whenever required can be uniformly applied in selected increments to the face of the grindstone.

These and other objects, adaptations, variations and modifications can be varied considerably by one skilled in the art and still be within the ambit of the fundamental concepts underlying my invention which is described clearly and definitively hereinbelow and of which the preferred embodiment is illustrated in the attached drawing forming a part hereof.

In the drawing for sake of convenience and ease of reference, like figures refer to similar numeral notations used in the specification. Therefore Figure 1 shows a perspective of my improved grindstone wheel dressing device resting in position on the frame (shown principally in the phantom sketch) of the grindstone wheel. For sake of clarity a clamping means, such as the ordinary C type clamp which can be used to fasten the dresser to the frame is not shown.

Figure 2 is a plan view, partly in section, of my improved grindstone dresser.

Figure 3 shows a sectional view of the edge of my improved grindstone dresser and the application of the dressing toothed gear to the periphery of the grindstone.

Figure 4 shows partly in section an end view of my improved grindstone dresser.

My improved grindstone dresser consists es-

sentially of a channelled substantially U-shape frame 10 whose ends 12 and 14 are open. Slidably mounted within the channel of the frame 10 and near the open ends 12 and 14 thereof are bearings 16 and 18. The bearings support the shaft 20 on which are mounted a plurality of the well known toothed dressing wheels 22 that are in contact with the grindstone periphery 24 shown in a phantom sketch.

To maintain the bearings 16 and 18 in parallel alignment a yoke-like member 26 is provided within the open area of the U-shaped channelled frame 10. The ends 28 and 30 of the said yoke are slidably engaged within the outstanding webs 10a and 10b of the channel of the U-shaped frame 10. A fastening means such as screws 32 fasten the ends 28 and 30 to the respective bearings. A reenforcing bar 34 transversely placed across the open end of the yoke 26 adds rigidity and strength and prevents wobble of the toothed gear like dressers 22 when pressure is applied during the dressing process.

At the upper part or apex of the yoke 26 is a hole 36. On each side of the hole 36 in the yoke are placed washers 38. Through the yoke hole 36 and washers 38 is inserted a spindle 40. The principal part of the uppermost portion thereof is a thread 42 which is engaged by a nut 44. The nut 44 is fixed immovably to the frame of the channel 10. The top of the spindle 40 terminates in a handwheel 46 which propels or retracts the threaded spindle portion 42 through the fixed nut 44 attached to the frame 10. Mounted on lower end of spindle 40 protruding thru the yoke hole 36 and washer 38 is a helical spring 48 which is retained in place by washer 50. The latter is prevented from falling of the spindle end 40 by a cotter pin 52 mounted thru the spindle 40.

Small bar 54 or if desired a bar slightly longer than the width of the channel frame 10 can be welded to the bottom and near the ends 12 and 14 of the frame 10. These bars 54 act as stops when the dresser is used, or at times, they provide a convenient place to hold the dresser to the frame of the grindstone by means of some fastening device such as an ordinary C-type clamp (not shown).

In actual use the bars 54 mounted on the lowermost part of the channel frame 10 are butted against or even placed on the edge of the frame 56 of the grindstone 24. It may be held against the frame by the operator or held in position by any holding means such as the conventional C-type clamp. In placing the dressing device in position for action it is necessary that the dressing teeth edges be placed in the desired position so that they contact uniformly the face 24 of the stone to be dressed.

When the device is fastened properly in place and with the grindstone revolving, the operator gradually turns the hand wheel 46 until the gear teeth 22 just barely touch the grindstone face 24. The spring 48 cushions the action of the hand wheel 46 and the movement of the yoke 26, since it acts on the washer 38 and in turn on the yoke 26, both of which are slidably mounted on the spindle 40. The operator then turns again slightly the hand wheel 46 and the teeth 22 are gradually but uniformly pushed across the entire face 24 of the grindstone surface. If the face 24 of the stone should be pitted or gouged then the spring 48 by acting on the yoke 26 thru the washer 38 keeps the teeth from striking into the pit and thus breaking it

open. In this manner grindstones badly pitted can be dressed smoothly for there is at all times a uniform pressure applied across the face of the stone.

In hand operation, the operator cannot maintain a uniform pressure across the face of the stone for the pit in the stone may come up unexpectedly or even at times there may be a hole in the stone which the dressing device may uncover. When this occurs, then the teeth of a hand operated grindstone dressing device strike thru and cause marring as well as damage.

As the stone is dressed down, more pressure is imparted by turning the knob 46 and which is transmitted from the screw 42 thru collar 41 on the washer 39 and in turn on the yoke 26. The latter transmits the pressure to the bearings 16 and 18 slidably mounted within the channel frame 10. As the bearings 16 and 18 move forward in parallel juxtaposition, they carry the shaft 20 likewise and thus in turn transmit the pressure to the cutting teeth 22. The pressure is applied uniformly to the face of the grindstone for the bearings move simultaneously in rigid parallel relationship. If for some reason, the teeth shall encounter a pit or a depression on the face of the stone, then the spring 48 prevents the teeth from falling into or following such depression. As the surface is dressed down, the teeth will eventually turn out a uniformly circular stone whose face will be dressed parallel to the edges of the teeth 22.

Having described hereinabove the essential concepts underlying my invention, I wish to include all those variations and modifications including the preferred embodiment as illustrated in the attached drawing that will fall within the scope of the spirit of my invention as defined in the hereunto appended claims.

I claim:

1. A grindstone dressing device comprising a U-shaped channel, the said U-shaped channel formed into a U-shaped frame, an opening between the extending arms of said U-shaped frame, the said U-shaped frame arms having open ends thereon, bearing members slidably mounted within the U-shaped channels forming the said open end arms, a means to hold said bearing members in parallel juxtaposition within the said open end arms, the said means to hold said bearing members in parallel relation comprising a V-shaped yoke, the ends of said yoke attached to said slidably bearing members, the apex of said yoke having therein an opening, a spindle inserted therethrough, screw threads on that part of the said spindle above the said opening in the apex of said yoke, a threaded nut mounted within the base of said U-shaped frame to engage the said threads on the spindle, a hand wheel mounted fixedly on that end of the said spindle protruding through said U-shaped frame base, and a spring mounted on that part of said spindle protruding through said apex of the yoke to keep the apex of said yoke in contacting juxtaposition with the said threaded portion of said spindle.

2. In the apparatus of claim 1, a helical spring mounted on the lower portion of said spindle protruding within the said yoke, to maintain the said apex in contacting juxtaposition with the threaded portion of the said spindle.

ANDREW J. ENGLE.
